UNITED STATES PATENT OFFICE.

ROLLS PERCIVAL LINK, OF WINCHMORE HILL, ENGLAND.

MACHINE FOR FORMING SHANKS OF COLLAR-STUDS.

1,180,161.

Specification of Letters Patent.

Patented Apr. 18, 1916.

Application filed October 5, 1914. Serial No. 865,177.

To all whom it may concern:

Be it known that I, ROLLS PERCIVAL LINK, a citizen of the United States of America, residing at Winchmore Hill, Middlesex, England, have invented a new and useful Improved Machine for Forming Shanks of Collar-Studs, of which the following is a specification.

This invention relates to an improved machine for forming shanks of collar studs of the kind in which the head of the stud has a hinge-like connection to the shank. Such shanks have heretofore been formed by subjecting them to the operation of various machines or tools to form or shape the several parts thereof.

According to the present invention, a machine is provided wherein after a sufficient length of wire has been cut from a strip or coil, the piece cut off is subjected to the operation of dies and punches which bring the said piece to its required finished shape. The machine operates automatically without requiring supervision of each operation on the stock and enables such shanks to be formed without the production of scrap metal excepting such as is produced by short waste ends of the strips or coils.

In the improved machine the wire from which the shanks are formed is fed in definite lengths, determined either by the construction of the machine, or by adjustment of parts thereof, and these lengths are cut off by a shearing slide from which each is delivered in turn to dies which, on closing, partly shape the wire to the required form and then hold the same while it is acted upon by punches which bring it to its final form. The introduction of a fresh length of wire into the dies ejects the previously formed shank therefrom.

The accompanying drawings show how the said invention can be conveniently and advantageously carried into practice.

In the drawings: Figure 1 is a side view of the improved mechanism. Fig. 2 is a plan thereof. Fig. 3 shows a section on the line A, A, Fig. 1 drawn to a larger scale, certain of the parts occupying different positions in their paths of travel to that in which they are shown in Fig. 2. Fig. 4 shows parts of the feeding and ejecting devices in section on the line B, B Fig. 3. Fig. 5 shows a section on the line C, C and Fig. 6 shows a section on the line D, D Fig. 4. Figs. 7, 8 and 9 are views illustrating the

shape of the shank in various stages in its formation. Fig. 10 shows a section taken on the line E, E Fig. 3. Fig. 11 is a detail plan view of a die and adjacent parts. Fig. 12 is a view mainly in section on the line F, F, Fig. 11, and Fig. 13 shows a section on the line G, G, Fig. 11. Fig. 14 shows a transverse section of the machine taken centrally through the dies and die operating toggle members.

Like reference numerals indicate corresponding parts throughout these drawings.

As shown in these drawings, 20 is a cam shaft passing through a slot in a cam bar 21 (Figs. 1 and 2) supported between and reciprocated by complementary cams 22 engaging rollers 23 projecting from the said bar which is slidably mounted in guides 24. A cam slot 25 (Fig. 5) in the bar 21 engages a roller 26 on a feed lever 27 having a forked or apertured end 28 engaging a lug 29 pivotally mounted on a stud 30 (Fig. 4) projecting from a slide 31 movable in guide ways 32. When the end 28 of the lever 27 is moved toward the left, Fig. 5, the lug 29 is rocked and clamps a wire 33 against a block 34 on the slide 31 and thereafter moves the wire 33 and slide 31 together until a definite length of the wire has been passed through a guideway 35 into a hole 36 in a shearing slide 37 movable in a slide-way 38 by means of a bell crank lever 39 link 40 and bar 41 carrying rollers 42 engaged by complementary cams 43 arranged similarly to the cams 22 and bar 21. The wire 33 passed into the hole 36 abuts against a bracket 44 acting as a length gage. When the slide 37 is moved, the portion of wire in the hole 36 is sheared from that in the guideway 35. As the slide 37 is thus moved, a die slide 46 movable in a guideway 47 by a connecting rod 48 and lever 49 carrying a roller 50 traveling in a groove in a cam 51, is simultaneously moved until these slides are brought to the positions shown in Fig. 2 with the hole 36 opposite dies 52, 53. The upper die 52 is movable relatively to the lower die 53 along dowel pins 54 and when the parts arrive in the position shown in Fig. 2, a cam slot 55 in the bar 21 moves a lever 56, Fig. 6, carrying a built-up bell-crank lever comprising three arms 57 secured together by pivot pins 59. When the intermediate arm 57 strikes against an abutment 58 (Figs. 12 and 14) the two outer arms 57 are turned about the axis of the pivots 59 so as

to come into contact with studs 60 (Figs. 3 and 13) projecting from the upper die 52, and raise the latter. Subsequently a cam slot 61 in the bar 21 moves an ejector rod 62 which thrusts the wire blank 45 from the hole 36 on to the shank forming recess in the lower die. The lever 56 is then moved so that the levers 57 are carried away from the studs 60 and the upper die is therefore lowered toward the lower die. At convenient times the ejector rod and shearing slide are returned to their initial positions. The die slide is next moved into position (Figs. 3 and 10) beneath die closing toggles 63 and between ram heads 64, 65. The head 64 is moved by a rod 66 carrying rollers 67 engaged by complementary cams 68 and the head 65 is moved by a link 69, lever 70 and rod 71 carrying rollers 72 engaged by complementary cams 73. As the heads 64, 65 move together a pair of levers 74 pivoted together at 75 and having a slotted connection with pins 76 on the said heads, are moved so as to force the knuckle of the toggles 63 upon the upper die 52 and close the dies whereby one end of the blank is flattened as shown at 77 Fig. 8. The shape of the forming recesses in the dies is apparent from a comparison of Figs. 10 and 11.

After the dies have closed, punches 78, 79 are brought by the heads 64, 65 to operate on the partly formed shank and respectively form in coöperation with the dies, a T-head 80 at one end and a shoulder 81 near to the opposite end, as shown in Fig. 9, this being the finished shape of the shank that it is required to produce. As soon as the punches have been drawn back from the work by outward movement of the heads 64, 65, the cam shaft 20 completes one revolution and the die slide commences to move toward the shearing slide. In the continued rotation of the cam shaft the shearing slide is moved and cuts off another piece of the wire, while the die slide is brought back to the position shown in Fig. 2, the lever 56 being then moved to raise the upper die 52 during which movement a sliding pin 82 (Fig. 10) 45 passing through the die is engaged by a pin 83 (Figs. 12 and 13) on a fixed part of the machine (such as the abutment 58) to cause the finished shank to be detached from the upper die if it adheres thereto. The new blank fed in by the ejector rod 62 pushes the formed shank beneath a retaining spring 84 on to a tray 85, carried by the lever 56. When the lever 56 swings back to the position shown in Fig. 6 a spring 86 engages the T-head of the formed shank so that when the lever next moves away from this spring 86 the formed shank is drawn off the tray and drops down a channel 87.

I claim:—

65 1. In a machine for forming shanks of

collar studs, a pair of forming dies, toggle levers, a reciprocating ram head, pivoted levers operatively connecting the toggle levers and the ram head to effect a closing movement of the dies when the ram head is moved in one direction, and a punch carried by the ram head to and from one end of the forming recess between the dies. 70

2. In a machine for forming shanks of collar studs, a pair of forming dies, toggle levers, a ram head operating the toggle levers to close the dies, a punch carried by the ram head to and from one end of the forming recess between the dies, an ejector rod, and a reciprocating slide moved to 75 carry the dies into alinement with the punch and the ejector rod alternately. 80

3. In a machine for forming shanks of collar studs, a pair of forming dies, toggle levers, reciprocating ram heads respectively 85 moving in alined paths on opposite sides of the dies, pivoted levers operatively connecting the toggle levers to the ram heads, and punches carried by the ram heads to and from the ends of the forming recess between 90 the dies.

4. In a machine for forming shanks of collar studs, a pair of forming dies, toggle levers, reciprocating ram heads respectively 95 moving in alined paths on opposite sides of the dies, pivoted levers operatively connecting the toggle levers to the ram heads, punches carried by the ram heads to and from the ends of the forming recess between the dies, an ejector rod, and a reciprocating 100 slide moved to carry the dies into alinement with the punch and the ejector rod alternately.

5. In a machine for forming shanks of collar studs a pair of forming dies, means 105 for raising the upper die from the lower die, means for closing the dies, and a reciprocating slide carrying the dies into operative relation to the die raising means and the die closing means alternately. 110

6. In a machine for forming shanks of collar studs, a pair of forming dies, means for raising the upper die from the lower die, means for closing the dies, a reciprocating 115 slide carrying the dies into operative relation to the die raising means and the die closing means alternately, a punch and means for moving the punch toward one end of the forming recess between the dies while the dies are closed. 120

7. In a machine for forming shanks of collar studs, a pair of forming dies, means for raising the upper die from the lower die, toggle levers operated to close the dies, and a slide moved to carry the dies into a 125 position opposite to the means for raising the upper die and a position beneath the toggle levers, alternately.

8. In a machine for forming shanks of collar studs, a pair of forming dies, means 130

for raising the upper die from the lower die, toggle levers adapted to close the dies, a punch adapted to engage in one end of the forming recess between the dies when 5 the dies are beneath the toggle levers, a reciprocatory slide moved to carry the dies into operative relation to the die raising means and die closing means alternately, and means for moving the punch toward 10 one end of the forming recess between the dies while the dies are closed.

9. In a machine for forming shanks of collar studs a pair of forming dies, means for raising the upper die from the lower die, toggle levers, ram heads, punches carried by the said ram heads, and pivoted levers operatively connecting the toggle levers to the ram heads to close the dies when 15 the punches are respectively advanced by 20 the ram heads toward opposite ends of the forming recess between the dies.

10. In a machine for forming shanks for collar studs, a pair of forming dies, means for raising the upper die from the lower die, 25 toggle levers, ram heads, punches carried by the said ram heads movable in the central plane of movement of the toggle levers, pivoted levers operatively connecting the toggle levers to the ram heads to close the 30 dies when the punches are respectively advanced by the ram heads toward opposite ends of the forming recess between the dies, and a reciprocatory slide carrying the dies into operative relation to the die raising 35 means and the toggle levers alternately.

11. In a machine for forming shanks of collar studs, a pair of forming dies, means for raising the upper die from the lower die, toggle levers, reciprocatory ram heads 40 respectively moving in alined paths on opposite sides of the dies, punches carried by the ram heads in the central plane of movement of the toggle levers, pivoted levers operatively connecting the toggle levers to 45 the ram heads to close the dies when the punches are respectively advanced by the ram heads toward opposite ends of the forming recess between the dies, an ejector rod situated opposite to the die raising means, 50 and a reciprocatory slide carrying the dies into operative relation to the die raising means and ejector rod and operative relation to the die closing means and the punches alternately.

55 12. In a machine for forming shanks of collar studs, a lower forming die, an upper forming die, an oscillatory lever, bell crank levers pivotally mounted on the oscillatory lever, an abutment in the path of the bell 60 crank levers to turn the latter on their pivots, and studs extending from the upper forming die into the path of the bell crank levers as they are moved by engagement with the abutment.

65 13. In a machine for forming shanks of

collar studs a lower forming die, dowel pins extending therefrom, an upper forming die movable on the dowel pins, an oscillatory lever, bell crank levers pivotally mounted on said lever, an abutment in the path of 70 the bell crank levers and studs extending from the upper forming die into the path of the bell crank levers so as to be moved by the said bell crank levers as they are moved by engagement with the abutment.

75

14. In a machine for forming shanks of collar studs, a shearing slide having a wire receiving hole therein, a pair of forming dies, means for raising the upper die from the lower die, means for bringing the slide 80 and the dies into alinement and an ejector operated to thrust a piece of wire from the hole in the shearing slide into the forming recess between the opened dies.

15. In a machine for forming shanks of 85 collar studs, a shearing slide having a wire receiving hole therein, a guideway, an intermittently operating feeding device for feeding wire through the guideway into the hole in the shearing slide, a gage limiting the 90 length of wire thus fed, a pair of forming dies, means for raising the upper die from the lower die, means for moving the slide relatively to the guideway to shear the wire 95 in the hole from the wire in the guideway and to bring the hole opposite to the opened dies, and an ejector for transferring the wire thus cut off to the forming recess between the dies.

16. In a machine for forming shanks of 100 collar studs, a shearing slide having a wire receiving hole therein, a pair of forming dies, a guideway, a slide, a block on the slide, a rocking lug on the slide, an oscillatory lever for moving the rocking lug to grip a 105 wire between the lug and the block, the slide and wire being thereafter moved together by the lever to advance the wire, a guideway through which the wire is moved into the hole in the shearing slide, means for moving the slide to cut the wire in the hole from the wire in the guideway, means for bringing the forming recess between the dies into 110 alinement with the wire receiving hole in the slide after the slide has thus moved, and means for transferring the wire cut off from the wire receiving hole to the forming recess between the dies.

17. In a machine for forming shanks of 120 collar studs, means for feeding wire to the machine, means for cutting off a predetermined length of the wire, a pair of forming dies, an oscillatory tray, a spring carried thereby, means for transferring the length of wire cut off into the forming recess between the dies and thereby thrusting a previously finished shank from between the dies into engagement with the spring, and a second spring arranged to engage the shank on the tray as the latter approaches one 125 130

limit of its movement and to withdraw the shank from the tray as the latter moves away from this second spring.

18. In a machine for forming shanks of collar studs, a lower forming die, an upper forming die, means for separating the upper die from the lower die, a pin slidably lodged in a hole in the said upper die, and a fixed pin engaging the slidable pin as the upper die separates from the lower die.

19. In a machine for forming shanks of

collar studs, a lower forming die, an upper forming die, means for separating the upper die from the lower die, means for detaching a finished shank from the upper die, and means for ejecting the detached shank from the forming recess between the dies. ¹⁵
